UNITED STATES PATENT OFFICE.

EMERICH H. VAVRA, OF CHICAGO, ILLINOIS.

RECEPTACLE-LINING.

1,218,723.

Specification of Letters Patent. Patented Mar. 13, 1917.

Application filed June 30, 1915. Serial No. 37,309.

To all whom it may concern:

Be it known that I, EMERICH H. VAVRA, a citizen of the United States, residing at Chicago, Cook county, State of Illinois, have invented certain new and useful Improvements in Receptacle-Linings, of which the following, taken in connection with the drawing, is a description.

My invention has for its object the production of a removable lining for receptacles of various kinds, more particularly those used for containing food products such as butter, ice cream, etc., which are easily contaminated if contained in a receptacle that is even slightly rusted or otherwise imperfect.

A further object of my invention is to produce a lining of this kind which shall be so cheap to produce that a lining can be used but once and thrown away and a fresh one used each time the receptacle is used.

A further object of my invention is to provide such a lining that may be folded into position inside of the receptacle without any fastening or securing devices of any kind to hold it in place, the sides and bottom portions thereof being sufficient to maintain it inside of the receptacle. Other objects and features of advantage of my invention will be apparent to those skilled in the art.

In the accompanying drawings I have illustrated what I now consider the preferred form of my invention, and in these drawings,

Figure 1 is a plan view of the blank out of which said lining is formed;

Fig. 2 is a plan view of the bottom lining portion;

Fig. 3 is a plan view of the bottom of the folded lining with the edge turned in;

Fig. 4 is a sectional view of a receptacle having my lining applied thereto.

Referring to the drawing, A represents a blank out of which the lining is formed, and which is preferably made of paraffin paper, or any other light, non-absorbent and odorless material, the curved edge will with the slightest pressure fold under the straight edge adjacent to it, thereby permitting a

rim to be formed practically automatically 50 as the lining is rolled into a cylinder and placed into a receptacle.

This blank is cut to any length or width desired to fit close to the inner wall of the receptacle within which it is to be used, being made large enough to be rolled into a cylinder with the edges a, a', meeting and overlapping a short distance.

Near one longitudinal edge of the blank I provide a scored or weakened line B, 60 where the outer edge of the lining may be bent at right angles to the body portion thereof. That portion of the blank extending from the scored line B to the edge is cut into a plurality of small sections or tabs 65 b, the outer edge of each section or tab being rounded upon one corner thereof, as at b', to facilitate the overlapping or folding of the edges of said tabs when the lining is turned into folded position. 70

When the meeting edges a, a', are brought together forming a cylinder out of the blank or body portion A, the lower end thereof is bent along the scored or weakened line B and the sections or tabs folded inwardly, as 75 shown in Fig. 3, the slit edges overlapping each other and forming a rim C which rests upon the bottom of the receptacle containing the lining.

A disk C' forms the bottom of the receptacle lining and rests upon the rim C inside of the cylindrical lining formed of the blank A. 80

D represents a receptacle in which the lining may be used, from which it will be 85 seen the walls of the receptacle do not come in contact with the contents of the receptacle at any time.

These linings are especially desirable for ice-cream freezers, butter tubs, etc., as they 90 are quickly placed in the receptacle, form a complete protection to the contents, and are readily removed when the receptacle is empty and a new lining is substituted.

I claim:

A receptacle lining comprising a single 95 piece of material adapted to be rolled into a cylinder with opposite edges thereof over-

lapped, said material having a scored or weakened line near one edge thereof, one edge of said material being slit or cut in sections to overlap each other and form an inwardly turned rim for the bottom of the receptacle, each of said sections having one side thereof curved to fold beneath the straight edge of the adjacent section, and a removable disk fitting inside of and rest-

ing upon said rim to form the bottom of the ¹⁰ lining receptacle, substantially as described.

In testimony whereof I have signed this specification in the presence of two subscribing witnesses.

EMERICH H. VAVRA.
